UNITED STATES PATENT OFFICE.

BERTWELL C. ROOT, OF MONTREAL, QUEBEC, CANADA, ASSIGNOR TO HYDRAULIC MACHINERY COMPANY LIMITED, OF MONTREAL, QUEBEC, CANADA.

PULP SCREEN.

Application filed November 12, 1921. Serial No. 514,835.

To all whom it may concern:

Be it known that I, BERTWELL C. Root, a citizen of the United States of America, and resident of the city of Montreal, in the 5 Province of Quebec and Dominion of Canada, have invented certain new and useful Improvements in Pulp Screens, of which the following is a full, clear, and exact description of the invention.

10 This invention relates to improvements in pulp screens and particularly to coarse or sliver screens, and the object of this invention is to provide a screen of simple, durable, and inexpensive construction which 15 will operate in a highly efficient manner.

The device comprises a screen drum formed of perforated plates, mounted between circular end plates. The drum is revolvably mounted by hollow trunnions between end plates which are suitably braced apart in a pit. A sliver trough is provided at an incline within the drum. Spray pipes are provided within the drum to wash the same and to wash the trough.

25 In the drawings which illustrate the invention, Figure 1 is an end elevation of the device;

Figure 2 is a side elevation with part of the drum broken away;

30 Figure 3 is a section on the line 3—3; Figure 2.

Referring more particularly to the drawings, 11 designates a pit constructed preferably of concrete and having in the bottom 35 thereof a sump 12 and at one end an extension 13 of less depth than the pit. A pair of end plates 14 are mounted in the pit at opposite ends thereof, and are held a fixed distance apart by tie-rods 15 and spacers 16. These end plates form supports for the 40 screen drum, and to this end each plate is provided with a bearing portion 17 provided with a removable cap 18 to permit insertion and removal of a drum without dis- 45 turbing the end plates 14.

The screen drum comprises a pair of similar circular end plates 19, each having a centrally disposed hollow neck or trun- 40 nion 20 adapted to rest in a bearing 17.

50 The end plates 19 are connected by screen plates 21 of any suitable construction. The interior of the drum is provided with a plurality of longitudinally extending trough- 55 shaped transporting plates or flanges 22. These plates are preferably arranged to be

concave side up on the ascending side of the drum and therefore concave side down on the descending side. One or both of the end plates is or are provided with a toothed circular driving ring 23 to mesh with one or more driving pinions 24 rigidly mounted in a driving shaft 25 journalled in the end plates 14. As will be clearly seen in Figure 2, the bottom of the pit extension 13 is about on a level with bottom of one 60 of the drum necks 20. The end of the drum adjacent the pit extension 13 is the inlet end. The end plate 14 at the inlet end of the drum, carries a bracket 26 extending through the neck and a short distance into 70 the drum. This bracket supports the upper end of an inclined sliver trough 27 which passes lengthwise and projects through the neck at the opposite end of the drum, being preferably supported by the end wall of the 75 pit and out of contact with neck of the drum, so as to be uninfluenced by drum rotation. A spray main 28 is provided extending into the drum, preferably through the inlet neck and branching into spray pipes 29 80 and 30. The pipe 29 is preferably located externally of the trough and adapted to spray the ascending side of the drum, while the other pipe 30 is preferably located within the trough and adapted to spray the upper part of the drum, directly over the trough. A third spray pipe 31 is provided 85 extending longitudinally and externally of the drum. A hood 32 of slightly greater width than the trough 27 is interposed between the spray pipe 31 and the drum, over the trough, to avoid conflict between the sprays from the pipes 30 and 31.

The operation of the device is as follows: 90 Pulp from digestors or grinders is fed into the pit extension 13, and runs from this extension through the drum neck into the drum itself in the usual manner. The drum is rotated and the pulp becomes spread over the inner surface thereof, the transporting 100 plates 22 serving to ensure that a large part of the surface of the drum is coated and active. These transporting plates also serve to hold slivers, bark fragments and other undesirable matter which has been separated 105 from pulp, against falling back into pulp in the bottom of the drum. The thin and finely ground portion of the pulp passes through the mesh of the screen 21 into the pit, from which it may be easily drained by reason 110

of the sump. The slivers, bark, etc. which will not pass through the screens either adhere to the inner surface thereof or are caught by the transporting plates and carried to the upper part of the drum. Water sprays from the pipe 29 wash the inner surface of the drums, and usually sweep slivers adhering to the same into the ascending transporting plates which serve to carry the slivers to a point over the trough 27. These sprays serve also to wash from the slivers pulp adhering thereto and to drive the pulp through the mesh of the screen. These clearly defined sprays will remove pulp which would not be dislodged by mere bathing of the screen with a quietly flowing stream of water and therefore their use results in the recovery of much pulp which would otherwise be discarded with the slivers and lost. Water sprays from the pipe 30 again wash the inner surface of the screens, and also wash slivers off the transporting plates, so that these slivers, etc. fall into the trough 27, through which they are floated, or washed by the current of water which falls back into the trough from the drum, and are thus discharged beyond the pit. Water from the spray pipe 31 flows over the hood 32 and washes the exterior of the screens to remove any pulp which has passed through, and is clinging to the screens, and washes same into the pit.

According to the present invention, the expensive iron vats generally employed are eliminated by the provision of a concrete pit and means to rotatably support the screen drum therein. This means that the purchaser neither buys nor pays transportation on a great amount of iron, but provides the pit or vat locally at a minimum of cost. The arrangement of stays between the end plates 14 provides a rigid and inexpensive support for the drum which may be easily assembled or taken apart. The removable portion 18 of the end plates permit of easy removal of the screen drum as a whole. The trough may be readily removed by lifting its upper end off the bracket 26 and sliding it out of the back end of the drum.

The arrangement of spray pipes ensures dislodgment of slivers and the like from the screen, so that the same does not become choked. The hood 32 not only prevents conflict of sprays from the pipes 30 and 31 but also receives the impact of jets from the pipe 31, so that the water flowing over the plate 32 trickles gently over the inside of the drum and washes pulp off the outer surface thereof without any danger of washing the pulp back into the drum.

Having thus described my invention, what I claim is:

1. In a pulp-screening device, a vat bearing plates in said vat, stay bolts and spacers holding said bolts rigidly in spaced relation and a screen drum rotatably supported by said plates.

2. A device according to claim one in which each plate is formed in two separable parts forming between them a bearing.

3. In a pulp screening device, a rotatable screen drum, internal transporting plates, carried by said drum, a sliver trough within the drum, a pair of spray pipes within the drum, one of said pipes being located externally of the trough, and arranged to direct jets of water against the ascending side of the drum, to wash slivers on to the transporting plates, and the second of said pipe being disposed within the trough and arranged to direct jets of water against the surface of the drum and the transporting plates above the trough to wash slivers therefrom into the trough.

4. In a pulp screening device, a rotatable screen drum, a sliver trough therein, a spray pipe within the drum arranged to direct jets of water against the inner surface of the drum above the trough, a second spray pipe disposed externally of the drum and arranged to direct jets of water toward the drum, and a hood interposed between said second spray pipe and the drum above the trough.

In witness whereof, I have hereunto set my hand.

BERTWELL C. ROOT.
